DESIGN FOR A SHOE

Benjamin Benjamin, Freeport, N. Y.

Application October 31, 1935, Serial No. 59,296

Term of patent 3½ years

To all whom it may concern:

Be it known that I, Benjamin Benjamin, a citizen of the United States of America, residing in Freeport, Long Island, county of Nassau, and State of New York, have invented a new, original, and ornamental Design for a Shoe, of which the following is a specification, reference being had to the accompanying drawing, forming part thereof.

I claim:

The ornamental design for a shoe, substantially as shown.

BENJAMIN BENJAMIN.
